ATTORNEY

UNITED STATES PATENT OFFICE.

PHILIP LEVINE, OF BROOKLYN, NEW YORK.

HOLDER FOR PENS, PENCILS, OR THE LIKE.

Application filed April 5, 1923. Serial No. 630,068.

To all whom it may concern:

Be it known that I, PHILIP LEVINE, a citizen of the United States, and a resident of the city of New York, borough of Brooklyn, in the county of Kings and State of New York, have invented a new and Improved Holder for Pens, Pencils, or the like, of which the following is a full, clear, and exact description.

This invention has relation to holders for pens, pencils or the like and has particular reference to a device of this character which is designed for attachment to the pocket of a garment or any other article where the same may be placed for receiving and retaining a pen, pencil or other implement of this nature.

One of the principal objects of the present invention is to provide a holder through which the pen, pencil or other implement is inserted and retained, which is so constructed as to facilitate the initial insertion of the implement into the embracing portion of the same.

As a further object the invention aims to provide a holder of the character described which is extremely simple in its construction, inexpensive to manufacture and which is thoroughly reliable and highly efficient in its purpose.

With the above recited and other objects in view, the invention resides in the novel construction set forth in the following specification, particularly pointed out in the appended claims and illustrated in the accompanying drawing, it being understood that the right is reserved to embodiments other than those actually illustrated herein to the full extent indicated by the general meaning of the terms in which the claims are expressed.

In the drawing—

Figure 1 is a fragmentary view of a portion of a garment and pocket, with the latter broken away and illustrating the holder in applied position.

Fig. 2 is a perspective view of the holder alone.

Fig. 3 is a face view of a holder element associated with a label.

Fig. 4 is a perspective view of a holder associated with a watch pocket.

Fig. 5 is a vertical sectional view therethrough taken approximately on the line 5—5 of Fig. 4.

Referring to the drawing by characters

of reference and more particularly to Figs. 1 and 2, the holder consists of relatively wide and narrow strips 10 and 11 which are preferably of elastic material and are stitched together at their opposite extremities as at 12. The strip 11 is further stitched vertically across its width by lines of stitching 13 which define a plurality of pencil or pen embracing loops 14. From one of the innermost lines of stitching 13 an inclined line of stitching 15 extends from the upper edge of the strip 11 to define between said inclined line of stitching 15 and the next adjacent line of stitching 13 an implement embracing loop 16 which produces at the upper end an enlarged entrance mouth 17 to facilitate the insertion of the pen, pencil or other implement through said loop. In practice the holder is secured within the mouth of the garment pocket 18 by a line of stitching 19 which extends along and adjacent the upper edge of the strip 10 and along and adjacent the end edges of said strip 10 and strip 11.

In the modified form of the invention illustrated in Fig. 3 a label 10^a is used in lieu of the strip 10 and the strip 11 is attached to the label by the vertical lines of stitching 13 and the end lines of stitching 12, while the inclined or angularly disposed line of stitching 15 extends at an angle from one of the innermost lines of stitching 13 and from the upper edge of the strip 11. It is, of course, understood that in this form the labels and holders may be manufactured in strip form and cut apart to produce the individual elements.

In the modified adaptation of the invention illustrated in Figs. 4 and 5 the holder consists of three strips of elastic 20, 21 and 22, the former strip 20 being secured to the rear face of the upper half of the strip 21 and the latter strip 22 to the front face of the lower half of the strip 21 by vertical end lines of stitching 23. The strip 21 is further secured by vertical longitudinal spaced lines of stitching 24 to the strip 20 to define a plurality of pen, pencil or other implement embracing loops 25. One of the innermost lines of stitching 24 has extending therefrom inwardly at an angle and from the upper edge of the strip 21 a line of stitching 26 which defines a central loop 27 having an enlarged entrance mouth 28. A watch pocket consisting of inner and outer pieces of material 29 and 30 is attached

to the holder by securing the upper edge 31 of the inner piece of material 29 to the lower edge of the strip 21 while the upper edge 32 of the outer piece of material 30 is secured to the lower edge of the strip 22. Extending inwardly at an angle from the upper edge of the strip 22 adjacent the opposite side edges thereof, inclined lines of stitching 33 are provided which terminate above the lower edge of the strip 22 and approximately at the lower edge of the strip 21, said lines of stitching 33 connecting the strips 21 and 22 and serving to produce a flared entering mouth for the watch pocket. It will thus be seen that in addition to constituting a holder and retaining means for pencils, pens or the like, the holder device in this form provides a safety pocket for a watch or other valuable articles, which is formed with an elastic or self-closing entrance mouth.

In the forms illustrated in Figs. 1 and 2 it is of course understood that the device may be attached in any desired manner to a desk, calendar, working man's aprons, walls, telephones, counters or school bags without departing from the spirit of the invention.

I claim:

1. The combination with a pocket, of a pocket mouth closing member and holder for pens, pencils or other similar implements, comprising a pair of elastic strips secured at their lower edges respectively to

the inner and outer edges of the pocket 35 mouth, and a third strip secured to the inner strip of said first mentioned pair of strips by parallel longitudinally spaced lines of stitching extending across the width of the inner strip, and an angularly disposed line of stitching extending from the upper edge of the inner strip at the juncture of the same with one of the parallel lines of stitching with said edge.

2. As a new article of manufacture, a 45 combined safety pocket and holder for pens, pencils or other similar implements adapted for arrangement within the pocket of a garment, comprising a pocket having an entrance mouth at its upper end, a pair of 50 elastic strips secured at their lower edges respectively to the inner and outer edges of the pocket mouth, and a third strip secured to the inner strip of the first mentioned pair of strips by parallel longitudinally spaced 55 lines of stitching extending across the width of the inner strip to define a plurality of implement receiving and embracing loops which dispose the implements in rear of the pocket member, and angularly disposed 60 lines of stitching extending from the upper edge of the outermost strip and through the intermediate strip to provide a reduced implement receiving and embracing portion having an enlarged entrance mouth for the 65 safety pocket.

PHILIP LEVINE.
